UNITED STATES PATENT OFFICE.

LEON LEWANDOWSKI, OF CLEVELAND, OHIO, ASSIGNOR OF ONE-THIRD TO NARCYZ RADZYMINSKI, OF CLEVELAND, OHIO.

COMBINED CURTAIN POLE AND ROLLER FIXTURE.

1,024,488.

Specification of Letters Patent.

Patented Apr. 23, 1912.

Application filed December 23, 1911. Serial No. 667,514.

To all whom it may concern:

Be it known that I, LEON LEWANDOWSKI, a citizen of the United States of America, residing at Cleveland, in the county of 5 Cuyahoga and State of Ohio, have invented certain new and useful Improvements in Combined Curtain Pole and Roller Fixtures; and I hereby declare the following to be a full, clear, and exact description of 10 the invention, such as will enable others skilled in the art to which it pertains to make and use the same.

This invention relates to new and useful improvements in combined curtain poles and 15 roller fixtures.

The object of this invention is to provide a fixture of this character which can be readily adjusted so as to accommodate different lengths of shade rollers without having to move the fixture itself and which also can be adjusted so that the curtain pole 20 can be arranged at any desired distance from the window casing.

My invention therefore consists in the 25 features of construction and combination of parts described in the specification, pointed out in the claims and illustrated in the accompanying drawings.

In the accompanying drawings Figure 1 30 is a view of a portion of a window casing with one of my improved fixtures secured thereon, and showing in dotted lines the curtain pole bracket swung backward against the casing. Fig. 2 is a section on line 2— 35 2, Fig. 1. Fig. 3 is a section on line 3—3, Fig. 2. Fig. 4 is a section on line 4—4, Fig. 2. Fig. 5 is a section on line 5—5, Fig. 1. Fig. 6 is a section on line 6—6, Fig. 1.

Again referring to the drawings *a* represents a section of a window casing to which 40 is secured my fixture. This fixture comprises a vertically arranged plate 1 which is provided with an integrally formed arm 2 which extends sidewise therefrom at a right 45 angle to said plate 1 so that it lies flat against the casing. This arm 2 is provided with a flange 3 at each side which extends longitudinally thereof so that the said arm is T-shaped in cross section. The plate 1 50 and the arm 2 are secured to the casing by means of screws 5. At the upper end of the plate 1 is formed a forwardly projecting ear 6 which is provided with a socket 7 and at the lower end is formed another forwardly 55 projecting ear 8 which is provided

with a socket 9. The curtain pole bracket consists of a horizontal arm 12 which is provided with a flange 13 at each side which extends longitudinally thereof so that the said arm is T-shaped in cross-section. At its 60 inner end said bracket arm 12 is provided with a downwardly extending stud 14 which fits into the socket 7 in the ear 6. The bracket arm 12 has a brace arm 15 formed integral therewith which at its lower end is 65 provided with a stud 16 which fits into the socket 9 in the ear 8. On top of the bracket arm 12 is arranged a bar 18 which at its forward end is provided with a hook 19. At its inner end at each side thereof said bar 70 18 is provided with an L-shaped flange 20, the said flanges being adapted to fit around the flanges 13 on the bracket arm 12 so as to fasten the said bar 18 to the arm 12 while at the same time leaving it free to slide on 75 the said arm 12. A thumb screw 21 extends through the said bar 18 and is adapted to engage the upper surface of the bracket arm 12 so that the said bar may be locked in any desired position. On the arm 2 is 80 slidably supported the standard 22 which supports the end of the shade roller. This standard is provided at its lower end at each side with an L-shaped flange 23, said flange being arranged to inclose the flanges 85 3 on the said arm 2 so as to hold the said standard on the said arm while permitting it to be slid back and forth on the said arm. The said standard 22 is provided with a small lip 24 which carries a set screw 25 90 which is adapted to engage the said arm 2 so as to lock the standard in any desired position on said arm. The standard 22 is provided with means for engaging the end of the shade roller which in this instance is 95 represented by an opening 26.

When applying my invention one of my fixtures is permanently secured at each side of the window casing and said fixtures are spaced apart the required distance to receive between them the shade roller and the curtain pole. After the plate 2 has been secured in position the standards 22 are adjusted back and forth so as to be the exact distance apart to accommodate the rollers 100 and this adjustability does away with the necessity of the exact measurement now required where the shade roller supports are permanently secured in position. After the shade rollers have been adjusted the curtain 105 110

pole is laid on the hooks 19 on the ends of the bars 18 and the pole can be adjusted toward or away from the window by sliding the bars 18 in or out on the bracket arms 12.

5 What I claim is,—

1. In a combined curtain pole and shade fixture, a plate provided with a forwardly projecting ear at its upper end and at its lower end, said ears being provided with 10 sockets, a bracket arm provided with a downwardly extending stud adapted to fit in the socket in the ear at the upper end of said plate, said bracket arm having a longitudinally extending flange at each side, a bar 15 provided with a hook at its forward end arranged on top of said bracket arm, said bar having a pair of L-shaped flanges at its opposite end adapted to engage the flanges on the bracket arm and a screw mounted on 20 said bar and adapted to engage with said bracket arm and a brace bar formed integrally with said bracket arm and provided with a stud adapted to fit into the socket in the ear at the bottom of the plate, for the 25 purpose set forth.

2. In a combined curtain pole and shade fixture, a plate provided with an integrally formed arm extending sidewise from said plate at a right angle thereto, said arm having a longitudinally extending flange at each 30 side thereof, a standard adapted to support

one end of the shade roller and having a pair of L-shaped flanges adapted to engage the flanges on said arm and having a lip which extends over said arm, a set screw 35 mounted in said lip and adapted to engage said arm, said plate having a forwardly projecting ear at its upper end and at its lower end, said ears being provided with sockets, a bracket arm provided with a downwardly 40 extending stud adapted to fit in the socket in the ear at the upper end of said plate, said bracket arm having a longitudinally extending flange at each side, a bar provided with a hook at its forward end arranged on top of said bracket arm, said bar having a pair of L-shaped flanges at its opposite end 45 adapted to engage the flanges on the bracket arm and a screw mounted on said bar and adapted to engage with said bracket arm and a brace bar formed integrally with said bracket arm and provided with a stud 50 adapted to fit into the socket in the ear at the bottom of the said plate, for the purpose set forth.

In testimony whereof, I sign the foregoing specification, in the presence of two witnesses.

LEON LEWANDOWSKI.
